UNITED STATES PATENT OFFICE.

AUGUST THONET, OF VIENNA, AUSTRIA-HUNGARY, ASSIGNOR TO THONET BROTHERS, OF SAME PLACE.

DESIGN FOR A CHAIR.

SPECIFICATION forming part of Design No. 22,012, dated November 22, 1892.

Application filed June 22, 1892. Serial No. 437,660. Term of patent 7 years.

To all whom it may concern:

Be it known that I, AUGUST THONET, a citizen of the Empire of Austria-Hungary, residing at Vienna, in the Empire of Austria-Hungary, have invented and produced a new and original Design for Chairs, of which the following is a specification.

This invention relates to a design for a chair in which the upward extensions of the hind legs terminate in a broad curved back plate having slightly-curved upper and lower edges and rounded-off corners.

The nature of my design is shown in the accompanying drawing, which represents a perspective view of the chair embodying my design.

A in the drawing represents the seat, and B the hind feet, of the chair, which are extended in upward direction above the seat

and having their upper ends terminating in a broad curved plate or back C, which is provided with curved upper and lower edges and with rounded-off corners. The back plate C is provided with suitable ornamentation on its face.

Having thus described my invention, I claim as new and desire to secure by Letters Patent—

The design for a chair, substantially as herein shown and described.

In testimony that I claim the foregoing as my invention I have signed my name in presence of two subscribing witnesses.

AUGUST THONET.

Witnesses:

W. B. MURPHY,
PAUL BERGER.
